REMOTE INDICATING APPARATUS

Roy D. Wilson, West Carrollton, Ohio, assignor to The National Cash Register Company, Dayton, Ohio, a corporation of Maryland

Filed May 20, 1963, Ser. No. 281,484

8 Claims. (Cl. 235—23)

The present invention relates to an indicating mechanism and more particularly to an indicating mechanism which may be disposed remotely from its parent machine, such as a cash register or an accounting machine.

The embodiment of the indicating mechanism disclosed herein is essentially of mechanical construction having electrical controls for controlling the positioning of a plurality of indicating means to display data set up in the parent machine.

It is an object of this invention to provide a new and improved indicating mechanism which may be operated 20 remotely from the parent machine.

Another object of this invention is to provide a remote indicating device capable of clearly displaying a maximum number of characters.

A further object of this invention is to provide a remote indicating device having novel controls for sequentially resetting and setting a plurality of indicating means in a minimum amount of time.

Another object of this invention is to provide a remote indicating device which is compact and of lightweight construction.

With these and incidental objects in view, the invention includes certain novel features of construction and combinations of parts, a preferred form or embodiment of which is hereinafter described with reference to the drawings which accompany and form a part of the specification.

Of the drawings:

FIG. 1 is a front view of the remote indicating device with the cover removed, showing the general arrangement of the various mechanisms which make up the remote indicating device, the first indicator mechanism being shown in a cutaway view disclosing the construction of the indicator.

FIG. 2 is a sectional view taken on line 2—2 of FIG. 1, showing the various parts which make up the clutch mechanism.

FIG. 3 is a sectional view taken on line 3—3 of FIG. 1, showing details of an indicator mechanism.

FIG. 4 is a sectional view taken on line 4—4 of FIG. 1, showing more details of an indicator mechanism.

FIG. 5 is a sectional view taken on line 5—5 of FIG. 1, showing the indicator control cam switches.

FIG. 6 is a detailed side view of an indicator mechanism, showing the clutch pawl disengaged from the clutch wheel.

FIG. 7, on the sheet of drawings containing FIGS. 1 and 2, is a time chart covering the operation of the various control switches and the clutch solenoid located in the parent machine and on the remote indicator device.

FIG. 8 is a schematic wiring diagram of the novel control circuit for controlling the operation of the remote indicator device.

2

Referring to the drawings, which illustrate a preferred embodiment of the present invention, FIG. 1 shows the general arrangement of the indicator mechanism, which includes a motor and clutch mechanism, generally indicated as 59, mounted on the left end of a support frame 60, nine indicator wheels 61, mounted adjacent to the clutch mechanism, and a cam switch actuating mechanism, generally indicated at 62, mounted on the right-hand end of the support frame 60.

The remote indicator mechanism of the present invention is used in conjunction with a cash register or any other type of calculating machine where the results of the machine operation are required to be displayed. Two examples of cash registers with which the remote indicator of the present invention may be used are disclosed in United States Letters Patent No. 2,972,422, issued to Mayo A. Goodbar et al. on February 21, 1961, and in United States Letters Patent No. 3,006,538, issued to Johann J. Deutsch on October 31, 1961. Both of these cash registers are equipped with readout switches which are mechanically set by operation of the cash register to represent the amount to be displayed by the remote indicator. Since the construction of the readout switches and their operation are fully disclosed in the above-cited patents, their representation and disclosure will be limited to the schematic diagram of FIG. 8. As will be explained more fully hereinafter, the various electrical controls disclosed in the present invention position the indicators according to the setting of the readout switches located in the parent machine.

Referring now to FIGS. 1 and 2, there is shown mounted on the left end of the support frame 60 a side frame 63, to which an A.C. drive motor 65 is mounted by means of screws 64. The side frame 63 has two mounting blocks 66 attached to it by means of screws 67, the blocks being used to mount the side frame to the support frame 60 by means of screws 68. The motor 65 has a drive shaft 69, which projects through the side frame 63 and has pinned to its end a drive pinion 70 (FIG. 2). Journaled in the side frame 63 is one end of an indicator drive shaft 71, the other end of which is rotatably supported by a side frame 72, mounted on the right-hand end of the support frame 60 in a manner similar to the side frame 63. A bronze bushing 73, mounted on the side frame 63, accommodates the end of the indicator shaft 71. Loosely positioned on the left end of the indicator shaft is a gear assembly for driving said indicator shaft. This assembly includes a control gear 74 secured on the hub of a ratchet wheel 75 (FIG. 2). Positioned between the control gear 74 and the bushing 73 is a spacer 76. The control gear 74 engages and is driven by the drive pinion 70. It will be seen from this construction that, upon operation of the motor 65, both the ratchet wheel 75 and the control gear 74 will be driven.

Associated with the ratchet wheel 75 is a clutch pawl 77 (FIGS. 1 and 2), rotatably mounted on a disc 78, which in turn has a hub portion 83 pinned to the indicator shaft 71. As may best be seen from FIG. 2, the disc 78 is provided with a slot 79 and a stud 80, to which is attached one end of a spring 81. The other end of the spring 81 is attached to a stud 82, mounted on the clutch pawl 77. With this arrangement, the spring 81 normally urges the clutch pawl 77 in such a direction as to bring it into engagement with the ratchet wheel 75.

Loosely mounted on the indicator shaft 71 adjacent to the disc 78 is a plate 84, on which is mounted a stop stud 85, which projects through the slot 79 of the disc 78 (FIG. 1). The end of the stop stud 85 is positioned adjacent to and in engagement with a flange 86 of the ratchet pawl 77, thereby normally preventing the ratchet pawl 77 from moving clockwise under the urging of the spring 81, as viewed in FIG. 2, to engage the ratchet wheel 75. The plate 84 also has a notch 87 (FIG. 2), located on its edge, into which is positioned one end of a control pawl 88. The other end of the control pawl contains a slot 89 (FIG. 2), into which is positioned a pin 90, mounted on the end of a plunger 91 of a clutch control solenoid L1, mounted on the support frame 60. The control pawl 88 is rotatably mounted on a second control pawl 93, which in turn is rotatably mounted on a stud 94 (FIG. 2) supported by the side frame 63. The control pawl 93 has, mounted on its end, a cam roller 95, which coacts with a cam 96 (FIGS. 1 and 2) pinned to the indicator drive shaft 71. The cam 96 has a notch 97, into which the roller 95 of the pawl 93 is normally urged by a spring 98, mounted between a stud 99 located on the pawl 93 and a stud 100 (FIGS. 1 and 2) mounted on the side frame 63. The pawl 93 also contains a slot 101 (FIG. 2) in which is positioned a pin 102 mounted on the control pawl 88, thus providing the rotatable support for said pawl 88.

With the construction just described, energization of the solenoid L1 retracts the plunger 91 against the urging of a spring 103 mounted between the pin 90 on the plunger and a stud 104 mounted on the side frame 63. Retraction of the plunger rotates the control pawl 88 clockwise as viewed in FIG. 2. This movement withdraws the pawl from engagement with the plate 84, thereby releasing the clutch ratchet pawl 77 and the plate for clockwise movement under the action of the spring 81. This results in the latching of the pawl 77 with the ratchet wheel 75, thereby coupling the indicator shaft 71 to the operation of the motor.

As will be explained more fully hereinafter, the motor drives the indicator shaft through two revolutions to provide an indicator operation, during which time the solenoid L1 is de-energized, thereby releasing its plunger 91 to the action of the spring 103, this action forcing the control pawl 88 into engagement with the notch 87 in the plate 84, stopping the plate 84 and the stud 85 mounted thereon. Stopping of the stud 85 forces the clutch ratchet pawl 77 to be disengaged from the ratchet wheel 75 due to the engagement of the stud 85 by the flange 86 of the ratchet pawl. Simultaneously with the engagement of the plate 84 by the pawl 88, the roller 95 of the pawl 93 engages the notch 97 of the cam 96, thus helping to stop the indicator shaft 71 and preventing any rebound reaction between the stud 85 and the edge of the slot 79 in the disc 78.

Mounted on the indicator shaft 71 are nine indicator assemblies, generally indicated as 61 in FIG. 1. Since all of the assemblies are of the same construction, only one will be described. As shown in FIGS. 1, 3, 4, and 6, each indicator assembly is composed of an index plate 105, mounted on a pair of support shafts 106, with a hub member 107 mounted between the index plates of each indicator assembly. Each of the support shafts 106 is mounted between the side frames 63 and 72 (FIG. 1). As shown in FIG. 4, the index plate has a center portion cut out with a series of notches 108 located on the inside peripheral edge. Associated with these notches is a clutch pawl assembly, which is shown in FIG. 6 and which comprises a clutch pawl disc 109 loosely mounted on the indicator shaft 71, a clutch pawl 110 pivotally mounted on the disc 109 by means of a stud 111, and a clutch wheel 112 pinned to the indicator shaft 71 adjacent the clutch pawl disc 109. The clutch pawl 110 is normally urged into engagement with a cut-out portion 113 of the clutch wheel 112 by a spring 114 mounted between a stud 115, mounted on the clutch pawl and extend-

ing through a cut-out portion 161 of the disc 109, and a stud 116 mounted on the clutch pawl disc 109. The clutch pawl 110 has a pair of fingers 117, which engage a stud 118, the end of which projects through a slot 119 located in the clutch pawl disc 109.

The stud 118 is mounted on the side of a stop selector plate 122, as shown in FIG. 3. The stop selector plate 122 has a plurality of teeth 123 on its peripheral edge and is mounted on a hub 124 (FIGS. 1 and 3), which in turn is loosely mounted on the indicator shaft 71. Attached to the clutch pawl disc 109 by means of rivets 121 (FIG. 1) is an indicator blank or drum 120 (FIGS. 1 and 3), which has the numerals 0 to 9 inclusive, indicated as 92 in FIG. 1, printed on its outer surface. Thus the engagement of the stud 118 by the fingers 117 of the clutch pawl 110 interconnects the disc 109 and the indicator blank 120 with the selector plate 122, thereby providing a unitary assembly, which will have basically the same movement.

Associated with the stop selector plate 122 is a stop pawl 125 (FIG. 3) rotatably mounted on the rear support shaft 106 and capable of being moved into an engaging position with any one of the teeth 123 of the selector plate 122. The lower portion of the stop pawl is attached to the plunger 126 of a solenoid 127 mounted on a bracket 162, which in turn is secured to the support frame 60. A spring 128, attached between a stud 129 mounted on the stop pawl 125 and a stud 130 mounted on the index plate 105, continuously urges the stop pawl 125 clockwise, as viewed in FIG. 3, thereby moving the pawl to a non-engaging position. This movement of the stop pawl is limited by a stop 131 (FIG. 3), which is formed from a portion of the index plate 105, as shown in FIG. 4. Coacting with the stop pawl 125 is a holding switch 163 (FIGS. 3 and 4) mounted on the bracket 162 and having a pair of contacts 164 and 165, which are operated by the stop pawl 125 through the engagement of the switch block 166 with a stud 167 mounted on the stop pawl. It will be seen from FIG. 3 that the contacts 164, 165 close upon the counter-clockwise movement of the stop pawl into engagement with the plate 122, and open when the pawl is in its non-engaging position. The function of the switch 163 will be described in connection with the explanation of the control circuit disclosed in FIG. 8.

It will be seen from this construction that, during the time the clutch pawl 110 is in engagement with the clutch wheel 112, the remaining parts of the indicator assembly 61 are rotated by the indicator shaft 71. If the solenoid 127 is energized at the appropriate time, the plunger 126 moves to the right, as viewed in FIG. 3, thereby rotating the pawl 125 against the action of the spring 128 into engagement with the stop selector plate 122. This action stops the selector plate 122, the stop pawl 110, and the disc 109. Both the pawl 110 and the disc 109 are stopped by the stud 118. Stopping of the disc 109 stops the indicator blank 120 in a position to display the appropriate character. As the indicator shaft 71 continues its rotation, the clutch pawl 110 is forced out of engagement with the clutch wheel 112 against the action of the spring 114. Referring to FIG. 1, it is seen that the stud 115, located on the clutch pawl 110, will be positioned within one of the notches 108 of the index plate upon the disengagement of the pawl from the clutch wheel, thus insuring the proper positioning of the character located on the indicator blank. Thus each indicator blank may be selectively positioned by the timely energization of its associated solenoid 127 to display the results of an operation of the parent machine. Due to the fact that each clutch wheel 112 is pinned to the indicator shaft 71, the clutch wheels continue to rotate until all of the appropriate indicators have been set.

As will be described more fully hereinafter, the indicator blanks 120 are set during one revolution of the indicator shaft, at the end of which the rotation of the indicator shaft is stopped. At the beginning of the next operation, after the solenoids 127 have been de-energized,

thereby allowing the stop pawls 125 to be returned to their non-engaging position by the action of the spring 128, the indicator shaft 71 is rotated one revolution, during which time all of the previously-set indicator assemblies 61 are picked up by the clutch wheels due to the action of the spring 114 (FIG. 6), forcing the clutch pawls into engagement with the clutch wheel 112. Thus, at the end of this first revolution of the indicator shaft, all of the indicator assemblies will be in their home position prior to the second revolution, during which time the various indicators are set by a control circuit which will now be described.

Referring to FIG. 8, there is shown a schematic diagram of the circuit for controlling the operation of the solenoids 127 of each indicator assembly. As previously disclosed, the remote indicator mechanisms of the present invention are used with a cash register of the type disclosed in the previously-cited Goodbar et al. and Deutsch United States patents. Each of these cash registers is disclosed as having a plurality of readout switches which are set by operation of the machine to represent the amount to be indicated. In the case of the Goodbar et al. patent, FIGS. 4 and 7 of that patent disclose the readout switch construction, and, in columns 15 and 16 of the specification, there is disclosed the setting of the readout switches by the indicator segment 532. FIG. 7 of the Deutsch patent discloses a similar type of switch arrangement.

The switches RS2-RS10 inclusive indicated in FIG. 8 of the drawings are similar to the switches disclosed in the above-cited references. Each switch is representative of an amount bank located in the parent machine. As indicated in FIG. 8, all the switches located above the line 132 are mounted on the parent machine, while those switches and electrical elements below the line are mounted on the remote indicator mechanism.

The switch SC1 shown in FIG. 8 corresponds to the switch 956 disclosed in FIG. 18 of the Goodbar et al. patent, and its operation is described in column 18 of that patent. The switch SC1 of the present invention is of the normally open type. The switch is controlled by the cam line of the parent machine, and its basic function is to prevent the operation of the remote indicator mechanism until the readout switches RS2-RS10 have been set by a machine operation of the type described in the Goodbar et al. and Deutsch patents cited previously.

The power supply as shown in FIG. 8 is of a standard design and consists of a rectifier 133, the load resistor R1, and the filter capacitor C1, to which is applied a current from an A.C. source over the conductors 134, 135. The drive motor 65 is shown connected across the conductors 134, 135, which provides the motor with an energizing pulse. The A.C. source to which the conductors 134, 135 are connected is located in the parent machine. It is obvious that any type of operational arrangement of the A.C. source may be had depending upon what conditions are required. Thus the A.C. source may be supplied to the motor 65 and the rectifier only during the operation of the parent machine or during some part of the operation of the machine. In the present example, the A.C. will be presumed to be supplied during the operation of the parent machine. After all of the readout switches RS2-RS10 inclusive have had their wipers set according to the data to be indicated by an operation of the parent machine, the switch SC1 closes, thereby providing an A.C. energizing pulse to the clutch control solenoid L1 from the rectifier 133, over the conductors 137, 138, and 139, the closed switch SC1, the conductor 140, the solenoid L1, and the conductor 168 to the other side of the rectifier 133.

FIG. 7 is a time chart showing the operation of various cam-operated switches and the clutch solenoid L1 during two complete revolutions of the indicator drive shaft 71. As described above, the closing of the switch

SC1 energizes the clutch control solenoid L1, thus latching the indicator drive shaft 71 to the drive motor 65. It will also be seen from FIG. 7 that the normally open switch SC2, a cam-operated switch mounted on the right side of the remote indicator mechanism, the operation of which will be described hereinafter, closes at sixty degrees of the first revolution of the drive shaft, thus providing an alternate energizing path to the solenoid L1 over the conductor 169 (FIG. 8). This arrangement allows the switch SC1 to open without dropping out the solenoid L1, thus allowing the drive shaft 71 to be rotated through two revolutions. As explained previously, during the first revolution of the drive shaft 71 all of the indicator assemblies that were actuated during the previous operation are picked up by the action of the spring 114 of each indicator assembly urging its associated clutch pawl 110 into engagement with the cut-out portion 113 of the clutch wheel 112 as the clutch wheel rotates with the drive shaft 71.

In order to control the positioning of the various indicator assemblies, two timing switches, a normally open switch SC3, and a normally closed switch SC4, each controlled by the operation of the indicator drive shaft, are used in conjunction with a three-level control switch RS1. Referring to FIGS. 1 and 5, there is shown, located on the right side of the indicator mechanism, a side frame 141, on which is mounted the three-level rotary switch RS1. Located on the peripheral surface of the switch are a series of contacts 142, which, as will be explained more fully hereinafter, are connected to each of the contacts of the readout switches RS2-RS10 inclusive located in the parent machine. Mounted adjacent the rotary switch is a cam shaft 143, rotatably supported by the support frame 72. Mounted on the cam shaft 143 are three cams, 144, 145, and 170, which control the operation of the switches SC3, SC2, and SC4, respectively. Coacting with the cam 144 is a cam roller 146 mounted on the end of a switch blade 147 of the normally open switch SC3. A similar roller 148 is mounted on the blade 149 of the normally open switch SC2. The normally closed switch SC4 has a roller 172 mounted on the blade 173. The switches SC2, SC3, and SC4 are mounted on brackets 150, which are secured to the support frame 72 by the screws 151. Rotation of the cam shaft 143 actuates each of the switches SC2, SC3, and SC4, depending on the configuration of its associated cam, in a manner well known in the art.

Mounted on the cam shaft 143 adjacent the switch RS1 is a control drive gear 152 (FIG. 5), which is driven by a pinion gear 153 mounted on the indicator drive shaft 71. The gears are so constructed that two revolutions of the pinion gear 153 drive the control gear 152 and the cam shaft 143 through one revolution. As shown in FIG. 1, mounted adjacent the gear 152 is a similar control drive gear 154 mounted on the wiper (not shown) of the rotary switch RS1, the wiper being of standard construction and driven by the pinion gear 153 through one revolution in the same manner as described above. During each revolution of the drive shaft 71, the contacts 142 on each level of the switch are sensed by the wiper.

The three levels of the rotary control switch RS1 are represented in FIG. 8 as RS1A, RS1B, and RS1C. The contacts 142 of the various levels are connected to similar contacts of the readout switches RS2-RS10 inclusive in the manner shown in FIG. 8. Referring to FIG. 7, it is seen that, as the indicator drive shaft 71 completes its first revolution, the normally open switch SC3 closes and the switch SC4 begins to close. This closing of the switch SC3 supplies an energizing pulse to the wiper of the switch level RS1C (FIG. 8) from the rectifier 133 over the load resistor R1, the conductor 171 to the switch SC3. This pulse is sent to each of the contacts representing the numeral nine of the readout switches RS2-RS10 at the end of the first revolution of the shaft 71. This pulse

continues until the wiper of the rotary switch RS1 has passed the zero position. By this time, the cam switch SC4 has closed, thereby providing an energizing pulse to the levels RS1A and RS1B over the closed switch SC3. Switch level RS1A provides contacts for the odd numerals, 1, 3, 5, and 7, while the switch level RS1B provides contacts for the even numerals, 2, 4, 6, and 8.

As shown in FIG. 8, each of the contacts 142 of the switch levels is wired over two positions to provide sufficient time for the energization of the appropriate solenoid 127 (FIGS. 3 and 4). The solenoids 127 of each indicator assembly are represented in FIG. 8 by the designation L2-L10 inclusive. Depending on the position of the wiper of the readout switches RS2-RS10, its associated solenoids 127 will be energized to stop the indicator blank 120 in a position to display the appropriate characters corresponding to the position of the wiper in a manner described previously. As the stop pawl 125 is moved into engagement with its associated stop plate 122 upon the energization of the solenoid 127, 20 the holding switch 163 closes, providing an alternate energizing circuit to the solenoid 127 from the rectifier 133 over the conductor 178, the closed switch SC3, the conductor 174, and the holding switch 163 to the appropriate solenoid L2-L10. The resistor R3, connected 25 across the switch SC3, eliminates any residual magnetism in the solenoids L2-L10 upon the subsequent opening of the switch SC3 at the end of the second revolution of the indicator drive shaft, thus facilitating the opening of the holding switches 163. The resistor R2 and the capacitor C2 suppress any spark across SC3 during its operation. Thus, at the end of the second revolution of the indicator drive shaft, the selected indicator blanks will be set to 30 indicate the amount set up in the readout switches of the parent machine.

Referring again to FIG. 7, it is seen that, at the beginning of the second revolution of the indicator drive shaft, the normally closed cam switch SC2 begins to open. When this occurs, the clutch control solenoid L1 is de-energized, thereby releasing the control pawl 88 (FIG. 2) to the action of the spring 103, thus preparing for the disengagement of the indicator drive shaft 71 from the motor drive at the end of the second revolution of the drive shaft 71. This insures that the drive shaft will be rotated only through two revolutions.

At the end of the second revolution of the drive shaft, as shown in FIG. 7, the wiper of the rotary switch RS1 has completed the sensing of all of the contacts of the levels of the rotary switch, the cam switch SC3 has opened, thereby de-energizing each of the actuated solenoids 127, the indicator drive shaft is in the home position, the clutch solenoid L1 is de-energized, the cam switch SC2 is in an open position, the cam switch SC4 is in its closed position, and the unit is in the home position ready for its next operation.

While the form of the invention shown and described herein is admirably adapted to fulfill the objects primarily stated, it is to be understood that it is not intended to confine the invention to the one form or embodiment disclosed herein, for it is susceptible of embodiment in various other forms.

What is claimed is:

1. In combination with an accounting machine apparatus having a plurality of switches differentially settable during a machine operation to represent an indexed amount, an indicating device remotely positioned from said machine apparatus and comprising

(a) a support member;

(b) a shaft member rotatably supported by said support member;

(c) driving means;

(d) means for coupling said driving means to said shaft member when operated;

(e) a plurality of indicator assemblies loosely mounted

5 on said shaft member, each of said assemblies including

(f) an indicator member having a plurality of characters positioned thereon;

(g) an engaging member rotatably supported on said indicator member;

(h) a rotatable member having a plurality of stop surfaces;

(i) means mounted on said rotatable member and connecting said rotatable member with said engaging member;

(j) a drive member secured to said shaft member;

(k) means normally urging said engaging member into engagement with said drive member to rotate the indicator assembly upon operation of said shaft member; and

(l) electromagnetic means associated with said rotatable member for stopping, when energized, said rotatable member by engaging one of said stop surfaces thereby disengaging said engaging means from said drive member thus stopping the indicator assembly to display one of said characters;

(m) circuit means connecting each of said differentially settable switches with one of said electromagnetic means;

(n) first switch means controlled by operation of said accounting machine apparatus for operating said coupling means;

(o) and a plurality of second switch means located in said circuit means and controlled by operation of said shaft member for enabling said differentially settable switches to selectively energize their associated electromagnetic means whereby the indicator assemblies are positioned to display characters representing the indexed amount.

2. In combination with an accounting machine apparatus having a plurality of switches differentially settable during a machine operation to represent an indexed amount, an indicating device remotely positioned from said machine apparatus and comprising

(a) a support member;

(b) a shaft member rotatably supported by said support member;

(c) driving means;

(d) coupling means including a first electromagnetic means for coupling said driving means to said shaft member when energized;

(e) a plurality of indicator assemblies loosely mounted on said shaft member, each of said assemblies including

(f) an indicator drum having a plurality of characters located on its peripheral edge;

(g) a pawl rotatably supported on said indicator drum;

(h) a rotatable member having a plurality of stop surfaces located on its edge, each surface corresponding to one of the characters located on said indicator drum;

(i) means interconnecting said rotatable member and said indicator drum;

(j) a drive member secured to said shaft member;

(k) means normally urging said pawl into engagement with said drive member thereby rotating the indicator assembly upon operation of said shaft member;

(l) a stop pawl rotatably mounted adjacent said rotatable member and capable of engaging one of said stop surfaces when operated; and

(m) second electromagnetic means for operating, when energized, said stop pawl for movement into engagement with one of said stop surfaces thereby stopping said rotatable member and said indicator assembly to display the character corresponding to the engaged stop surface;

- (n) circuit means connecting each of said differentially settable switches with one of said second electromagnetic means;
- (o) first switch means controlled by operation of said accounting machine apparatus for energizing said first electromagnetic means; 5
- (p) and a plurality of second switch means located in said circuit means and controlled by operation of said shaft member for enabling the differentially settable switches of the accounting machine apparatus to selectively energize their associated second electromagnetic means whereby the indicator assemblies are positioned to display the indexed amount.
- 3. In combination with an accounting machine apparatus having a plurality of switches differentially settable during a machine operation to represent an indexed amount, an indicating device remotely positioned from said machine apparatus and comprising 15
  - (a) a support member;
  - (b) a shaft member rotatably supported by said support member;
  - (c) driving means;
  - (d) coupling means including a first electromagnetic means for coupling said driving means to said shaft member when energized; 25
  - (e) a plurality of indicator assemblies loosely mounted on said shaft member, each of said assemblies including
    - (f) an indicator drum having a plurality of characters located on its peripheral edge;
    - (g) a pawl rotatably supported on said indicator drum;
    - (h) a rotatable member having a plurality of stop surfaces located on its edge, each surface corresponding to one of the characters located on said indicator drum; 35
    - (i) means interconnecting said rotatable member and said indicator drum;
    - (j) a drive member secured to said shaft member;
    - (k) means normally urging said pawl into engagement with said drive member thereby rotating the indicator assembly upon operation of said shaft member;
    - (l) a stop pawl rotatably mounted adjacent said rotatable member and capable of engaging one of said stop surfaces when operated; and 45
    - (m) second electromagnetic means for operating, when energized, said stop pawl for movement into engagement with one of said stop surfaces thereby stopping said rotatable member and said indicator assembly to display the character corresponding to the engaged stop surface; 50
    - (n) circuit means connecting each of said differentially settable switches with one of said second electromagnetic means; 55
    - (o) first switch means controlled by operation of said accounting machine apparatus for energizing said first electromagnetic means whereby said shaft member is driven through two revolutions; 60
    - (p) second switch means located in said circuit means and operated by rotation of said shaft member for sequentially supplying, when enabled, an energizing pulse to each of said differentially settable switches; 65
    - (q) and third switch means controlled by rotation of said shaft member for enabling said second switch means during the second revolution of the shaft member whereby the second electromagnetic means of the indicator assemblies are selectively energized to position their assemblies so as to display the indexed amount. 70
  - 4. In a cyclically operable indicator mechanism the combination of
    - (a) a drive member operable through two revolutions; 75

- (b) a first wheel loosely mounted on said drive member;
- (c) a plurality of characters distributed around the periphery of said first wheel;
- (d) an engaging member rotatably supported on said first wheel;
- (e) a second wheel loosely mounted on said drive member adjacent said first wheel, said second wheel having a plurality of tooth portions positioned according to the position of a corresponding character on said first wheel;
- (f) means interconnecting said engaging member and said second wheel;
- (g) a third wheel secured to said drive member, said third wheel having a slot which cooperates with said engaging member when so positioned;
- (h) means normally urging said engaging member into engagement with the slot of said third wheel for driving both first and second wheels during the first revolution of said drive member;
- (i) electromagnetic means engaging, when energized, one of said tooth portions of said second wheel to disengage said engaging means from said third wheel thus positioning the second wheel to display the character corresponding to the engaged tooth portion;
- (j) and control means operated by said drive member for selectively energizing said electromagnetic means during the second revolution of said drive member whereby the selected character is displayed.
- 5. In a cyclically operated indicating mechanism the combination of
  - (a) a shaft operable through two revolutions;
  - (b) a drum member loosely mounted on said shaft, said drum member having a plurality of characters distributed around its peripheral edge;
  - (c) a pawl rotatably supported on said drum member;
  - (d) a disc member loosely mounted on said shaft adjacent said drum member, said disc member having a plurality of tooth portions located on its peripheral edge, each tooth portion positioned according to the position of a corresponding character on said drum member;
  - (e) means interconnecting said pawl and said disc member;
  - (f) a drive member secured to said shaft, said drive member having a slot which cooperates with said pawl when so positioned;
  - (g) resilient means urging said pawl into engagement with the slot of said drive member whereby the drum member and the disc member are driven by the shaft during the first revolution;
  - (h) electromagnetic means, operated during the second revolution of the shaft, for selectively stopping said disc member by engaging one of said stop portions whereby said pawl is disengaged from said drive member;
  - (i) and means for holding said pawl in a disengaged position whereby the drum member is positioned to display the character corresponding to the engaged tooth portion.
- 6. In a cyclically operated indicating mechanism the combination of
  - (a) a shaft operable through two revolutions;
  - (b) a drum member loosely mounted on said shaft, said drum member having a plurality of characters distributed around its peripheral edge;
  - (c) a first pawl rotatably supported on said drum member;
  - (d) a disc member loosely mounted on said shaft adjacent said drum member, said disc member having a plurality of tooth portions located on its peripheral edge, each tooth portion positioned according to the position of a corresponding character on said drum member;

11

- (e) means interconnecting said first pawl and said disc member;
- (f) a drive member secured to said shaft, said drive member having a slot which is engaged by said first pawl when so positioned;
- (g) resilient means urging said first pawl into engagement with the slot of said drive member thereby allowing the drum member and the disc member to be driven by the shaft during the first revolution;
- (h) a second pawl mounted adjacent said disc member and movable, when activated, to a position engaging one of said tooth portions;
- (i) electromagnetic means, operated during the second revolution of the shaft, for actuating said second pawl into engagement with one of said tooth portions thereby stopping said disc member and allowing said first pawl to be disengaged from said drive member;
- (j) and a stationary disc mounted adjacent said drum member and having a plurality of cut-out portions, each portion capable of holding said first pawl in a disengaged position whereby the drum member is positioned to display the character corresponding to the engaged tooth portion.

7. In combination with an accounting machine apparatus having a plurality of switches differentially settable during a machine operation to represent an indexed amount, an indicating device remotely positioned from said machine apparatus and comprising

- (a) a support member;
- (b) a shaft member rotatably supported by said support member;
- (c) driving means;
- (d) coupling means including a first electromagnetic means for coupling, when energized, said driving means to said shaft member for driving said shaft member through two revolutions;
- (e) a plurality of indicator assemblies loosely mounted on said shaft member, each of said assemblies including

  - (f) a drum member loosely mounted on said shaft member, said drum member having a plurality of characters distributed around its peripheral edge;
  - (g) a first pawl rotatably supported on said drum member;
  - (h) a disc member loosely mounted on said shaft adjacent said drum member, said disc member having a plurality of tooth portions located on its peripheral edge, each tooth portion positioned according to the position of a corresponding character on said drum member;
  - (i) means interconnecting said first pawl and said disc member;
  - (j) a drive member secured to said shaft member, said drive member having a slot which is engaged by said first pawl when so positioned;
  - (k) resilient means urging said first pawl into engagement with the slot of said drive member thereby allowing the drum member and the disc member to be driven by the shaft member during its first revolution;
  - (l) a second pawl mounted adjacent said disc member and movable, when actuated, to a position engaging one of said tooth portions;
  - (m) second electromagnetic means for actuating, when energized during the second revolution of said shaft member, said second pawl into engagement with one of said tooth portions thereby stopping said disc member whereby said first pawl is disengaged from said drive member and the drum member is positioned to display the character corresponding to the engaged tooth portion;
  - (n) and means for holding said first pawl in a disengaged position;

- (o) circuit means connecting each of said differentially settable switches with one of said electromagnetic means;
  - (p) first switch means controlled by operation of said accounting machine apparatus for energizing said first electromagnetic means;
  - (q) and a plurality of second switch means located in said circuit means and controlled by operation of said shaft member for enabling said differentially settable switches to selectively energize their associated second electromagnetic means whereby the selected indicator assemblies are positioned to display the indexed amount.
8. In combination with an accounting machine apparatus having a plurality of switches differentially settable during a machine operation to represent an indexed amount, an indicating device remotely positioned from said accounting machine apparatus and comprising
- (a) a support member;
  - (b) a shaft member rotatably supported by said support member;
  - (c) driving means;
  - (d) coupling means including a first electromagnetic means for coupling, when energized, said driving means to said shaft member for driving said shaft member through two revolutions;
  - (e) a plurality of indicator assemblies loosely mounted on said shaft member, each of said assemblies including
    - (f) a drum member loosely mounted on said shaft member, said drum member having a plurality of characters distributed around its peripheral edge;
    - (g) a first pawl rotatably supported on said drum member;
    - (h) a disc member loosely mounted on said shaft adjacent said drum member, said disc member having a plurality of tooth portions located on its peripheral edge, each tooth portion positioned according to the position of a corresponding character on said drum member;
    - (i) means interconnecting said first pawl and said disc member;
    - (j) a drive member secured to said shaft member, said drive member having a slot which is engaged by said first pawl when so positioned;
    - (k) resilient means urging said first pawl into engagement with the slot of said drive member thereby allowing the drum member and the disc member to be driven by the shaft member during its first revolution;
    - (l) a second pawl mounted adjacent said disc member and movable, when actuated, to a position engaging one of said tooth portions;
    - (m) second electromagnetic means for actuating, when energized during the second revolution of said shaft member, said second pawl into engagement with one of said tooth portions thereby stopping said disc member whereby said first pawl is disengaged from said drive member and the drum member is positioned to display the character corresponding to the engaged tooth portion;
    - (n) and a disc mounted adjacent said drum member and having a plurality of cut-out portions, each portion capable of holding said first pawl in a disengaged position;
    - (o) circuit means connecting each of said differentially settable switches with one of said second electromagnetic means;
    - (p) first switch means controlled by operation of said accounting machine apparatus for energizing said first electromagnetic means;
    - (q) a plurality of second switch means located in said circuit means and controlled by operation of said

13

shaft member for enabling said differentially settable switches to selectively energize their associated electromagnetic means;
 (r) and a plurality of third switch means, one for each second electromagnetic means and operable upon energization of its associated second electromagnetic means for providing said electromagnetic means with an additional energizing circuit whereby the selected indicator assemblies are positioned to display the indexed amount during the second revolution of said shaft member.

UNITED STATES PATENT OFFICE
CERTIFICATE OF CORRECTION

Patent No. 3,179,335

April 20, 1965

Roy D. Wilson

It is hereby certified that error appears in the above numbered patent requiring correction and that the said Letters Patent should read as corrected below.

Column 2, line 16, for 2,972,422" read -- 2,972,442 --.

Signed and sealed this 24th day of August 1965.
